UNITED STATES PATENT OFFICE.

LYMAN S. STEVENS, OF BALTIMORE, MARYLAND; CORA STEVENS ADMINISTRATRIX OF
SAID LYMAN S. STEVENS, DECEASED.

REVERSIBLE INTERNAL-COMBUSTION ENGINE.

1,331,399.

Specification of Letters Patent.

Patented Feb. 17, 1920.

Application filed June 9, 1915. Serial No. 33,112.

To all whom it may concern:

Be it known that I, LYMAN S. STEVENS, a citizen of the United States, residing at Baltimore, State of Maryland, have invented 5 certain new and useful Improvements in Reversible Internal-Combustion Engines, of which the following is a specification.

This invention relates to internal combustion engines used for converting the latent 10 thermal energy of hydrocarbon, oxy-carbon, gaseous evaporates, and other combustible gases into dynamic energy for power purposes.

An object of my invention is to provide 15 means for making an internal combustion engine as readily and certainly reversible as is the reciprocating steam engine.

Another object is to provide means for scavenging fully the exhaust charge in the 20 cylinder, and thoroughly ejecting all, or practically all, of the burned products of combustion, so that the incoming charge will be capable of being ignited at a low temperature and compression, due to the fact 25 that there are none of the carbon dioxid gases left to contaminate the new charge of fuel and air.

Further objects are to provide means for proportioning the fuel to the air in a manner 30 that is absolutely under the control of the operator; to provide a mixture of fuel and air that may be ignited at any part of the piston stroke with certainty; and to provide means for starting the engine with the 35 pressure of the fuel or other gas in either direction as desired.

These objects are attained in the manner and by the means hereinafter described and claimed, reference being had to the accompanying drawings, in which:—

Figure 1 is a side elevation, partly in section, of an internal combustion engine embodying my improvements.

Fig. 2 is an enlarged detail side elevation, 45 partly in section, of the valve and firing device reversing gear.

Fig. 3 is an enlarged detail view of the valve gear starting device.

Fig. 4 is a detail sectional view taken on 50 the line IV—IV, Fig. 3.

Fig. 5 is an enlarged detail sectional view of the engine piston with its cooling system applied.

Similar numerals of reference denote corresponding parts in the several views.

Referring to Fig. 1, the valves 2 are connected to a reservoir of gas under a pressure sufficient to actuate the engine part of a revolution, or until the engine has taken in a charge of gas at the other end of the piston 60 8, which will occur at a one-half revolution of the crank shaft 4. This gas may be of any character, such as air under pressure, though preferably I employ the fuel gas used with the engine, as the same is present 65 under sufficient pressure, as hereinafter will be described. The valves 2 are then closed and the engine is in condition to operate at the will of the operator without other means than the impulse from the explosions of internal fuel charges.

The engine is shown as being at the top of the stroke, and at the moment of receiving an impulse from the firing of the charge at that end, and the sequence of events will be 75 as follows:—The engine crank rotating to the right will at the position shown exhaust the products of the burned charge below the piston 8, and be receiving a scavenging charge of air from the air pump receiver 5 80 through valve 6, and this cleaning charge will be injected at a pressure of about four pounds per square inch, and as the capacity of the air pump cylinder is about fifty per cent. greater than the cubic contents of the 85 cylinder 7, the burned products of the last charge effectually will be cleaned out, and none of the objectionable carbon dioxid will remain in the cylinder to contaminate the incoming charge.

As the piston 8 passes the opening to valve 6 on the down stroke, the lower valve 1 will open and admit a portion of gas or vapor into the cylinder below piston 8 at a pressure of about twenty pounds, which gas 95 cannot escape into the exhaust as all ports of egress are closed. In an application for Letters Patent filed by me May 25, 1915, Serial No. 30,310, for improvements in apparatus for measuring the charge of fuel 100 and air in internal combustion engines, I have disclosed an improved means for supplying a measured charge under pressure to the working cylinder or cylinders of such an engine, which mechanism is embodied in the 105 present invention, as follows: The gas or vapor admitted through valve 3^a into the pipe 3^b, is measured by means of the adjustable piston 3^c in the measuring cylinder 10, as described in said application. This 110

charge thus will be discharged into the cylinder 7 below piston 8 until the pressure in said cylinder 7 and in the measuring cylinder 10 and pipe 3^b are equalized, at which time the cam 11 will close the valve 1 and the pressure will be completed by the further downward movement of the piston. On the up-stroke, this cycle of operations will be repeated.

10 The air pump 12 is attached to the main engine by means of beam 13 and connecting rods 14 and 15, and its function is to supply a charge of pure air into the cylinder 8 at each end of the stroke, and at the same 15 operation to clear the cylinder of the products of combustion of the last charge of gas and air. A small proportion of carbon dioxide has a most potent effect in raising the temperature at which the fuel charge 20 will ignite, and as this heat must be supplied by the heat of compression, it is evident that the compression will have to be carried to a high point to make certain the 25 explosion of the charge, which is the reason for the uncertainty of the combustion in the usual engine. For this reason the air pump should be about fifty per cent. greater in cylinder capacity than the engine cylinder. The air will be delivered at about four 30 pounds per square inch pressure to the cylinder 7, and the piston 8 having uncovered the exhaust opening 9 just before the uncovering of the air admission port 6, the pressure in cylinder 7 will be at less than 35 one pound when the air charge is admitted to said cylinder.

The operation and functions of the cam 11 are as follows:—Upon the rotation of the crank on shaft 4 to the right from the 40 position shown in Fig. 1, an eccentric 17 is operated through the gears 18, 19 and 20, from shaft 4. This eccentric 17 operates rod 16, which in turn oscillates the cam 11 and causes the projection 21 thereon to actuate the valve stem 22 and open the valve 3^a, thereby admitting a charge of compressed 45 gas from a supply cylinder (not shown) to the cylinder 10 and its supply pipes 3^b. The further movement of the cam 11 causes the 50 projection 24 thereon to engage the lower end of shaft 23, thereby opening the upper valve 1 to permit a discharge of compressed charge from pipe 3^b into the upper end of cylinder 7. Upon the return movement of 55 rod 16, due to the further rotation of the cam 17, the projection 21 again opens valve 3^a to admit a fresh charge to the cylinder 10 and pipe 3^b, and as the rod 16 approaches its lowermost limit of movement the projection 60 24 on cam 11 will contact with the upper end of rod 23, thereby opening the lower valve 1 to admit the charge from cylinder 10 and pipe 3^b into the lower end of cylinder 7.

65 The cubic contents of cylinder 10 and its

pipe 3^b may be changed readily by altering the position of the piston 3^c manually through screw rod 26 and wheel 27, as the movement of said piston 3^c outward will increase the charge, which will cause a 70 higher compression in the cylinder 7 and increase the speed of the engine. This engine speed may be varied as much as seventy per cent. by the piston 3^c, and the proportions altered from about twenty to one to four to 75 one in the cylinders, according to the quality of gas and the desired speed of the engine.

I also find that it is advisable to enrich the fuel charge at the time of starting the engine, as it will be necessary to secure an 80 impulse at a low compression, and a greater impulse will be required at that time. I accomplish this by moving the piston 3^c outwardly to increase the initial supply of gas in cylinder 10 and pipe 3^b, and when the 85 engine has started said piston 3^c may be again changed to suit the desired speed of the engine.

Referring to Fig. 2, which represents the valve and firing device reversing gear, the gear 18 is provided with a long boss sleeve 28 in which is an interior helical groove or set of grooves, in which fit the helical splines of a sliding sleeve 29, which may be adjusted by the collar 29^a, and in its motion 95 is caused to rotate part of a revolution in one direction, and this helical splined sleeve 29 has a set of interior grooves also helical that engage helical splines 30 on shaft 31 and these being of the opposite direction to 100 the splines on the sleeve 28 will cause a still further motion of the shaft 31 on which eccentric 17 is secured, and by which, through rod 16, motion to cam 11 is transmitted. The pitch of these splines are so related that 105 the full throw of the shaft 31 is secured for a forward or backward motion of the engine by passing the sleeve 28 from one extreme end position to the other extreme, and this will cause the valve gear and the 110 firing devices to assume their proper positions in regard to the crank shaft 4.

Fig. 3 represents the valve gear starting device, to be used in case there is no charge of combustible gases in the cylinder, and in 115 which 32 is a cam that is actuated by a rod 33 which is attached at the lower end to an eccentric 34, shown in Fig. 1. This eccentric 34 is mounted in identically the same manner as is the eccentric 17, hereinbefore 120 described, so that its position may be shifted manually by the movement of its splined sleeve similar to sleeve 29 of eccentric 17. The oscillations of this cam 32 serve to open 125 and close valves 2, similar to valves 1, to admit the high pressure gas to the cylinder 7 and actuate the piston 8 as the pressure may be admitted to either end of the cylinder 7 as the exigencies may demand, as will be understood. As the cam 32 presses 130

against either of the blocks 35 it raises its valve stem 38 and actuates its valve 2 in the following manner: Each block 35 normally is in contact with a toe 36 fixed to 5 the end of each rod 38, and when actuated by cam 32 moves said toe and with it its rod 38 to open its valve 2. Said blocks 35 are slidable vertically on a common rod 40, and have a tongue and groove connection with 10 their toes 36, as shown in detail in Fig. 4. Said rod 40 is movable toward and from the cam 32 by means of link 42 and arm 43 on shaft 44 and at its ends is carried in blocks 41 slidably mounted in suitable fixed 15 guides 37.

When it is desired to start the engine, the operation is first to place the splined sliding sleeve of said eccentric 34 in position for the proper desired direction of rotation, 20 and then force the rod 40 and sliding blocks 41 inward by means of the link 42 and arm 43 on shaft 44, to the position shown in Fig. 3, when the cam 32 will engage the proper toe and admit the pressure gas to 25 the proper end of the cylinder 7 for the desired impulse.

Fig. 5, which represents the piston and crosshead trunnion with the water cooling system for the piston ends, shows in section 30 the piston with the cross head trunnion passing through the same, and shows the water cooling pipes in elevation. The cooling water first is introduced through pipe 45 which is held stationary, while pipe 48, 35 which telescopes therein, is fastened securely to the trunnion end of piston 9. As the piston travels from end to end of its stroke the pipes 48 and 49 travel through their respective packing boxes 47, the water 40 passing through pipe 45 to pipe 48 and then through the trunnion 55 and pipe 50 to the chamber in piston end 51, and through this to pipe 52 and then to piston end 53 and up through pipe 54 to the other 45 end of trunnion 55 and then through the pipes 49 and 46. This circulation effectually will cool the piston ends 51 and 53 and prevent any premature explosion due to the gradual heating of the piston ends 50 to a red heat due to constant operation. Suitable check valves 56 and 57 in the pipes 58 and 59, leading into pipes 45 and 46 are necessary in pumping the water of the 55 circulation through the pistons and cylinder cooling chambers, and the stroke and diameter of the pipes 48 and 49 control the amount of water that is used as a cooling medium for each cylinder.

This cooling water first cools the pistons 60 and then is circulated through the cylinder water cooling chambers and as the water maintains the piston heads at a low temperature the ignition of the compressed charge is by this cause eliminated.

65 In my engine I use an exterior air pump

for purposes of scavenging, as I find that it is impossible effectively to expel all of the burned gases of an internal combustion engine unless the scavenging charge is sufficiently great to fill the cylinder completely, 70 and above this amount, approximately fifty per cent. more air should be passed through the cylinder to eliminate the carbonic acid gas of combustion. The ordinary two and four cycle engines rely upon a volume of 75 air equal to or less than the displacement of the piston in its stroke, which is about eighty per cent. of the contents of the cylinder, and when the piston is going through the scavenging process at the exhaust period, there is about twenty per cent. or more, 80 of the old charge remaining in the cylinder at the beginning of the next compression stroke, and this twenty per cent., in the well known manner, prevents combustion 85 except at a high temperature, consequently they will "fire" at high compression only, and this with no certainty. But in my engine, I use a volume of about fifty per cent. in excess of the cubic contents of the explosive chamber when the piston is beginning the compression stroke.

When the explosive impulse is in effect, the piston of my engine moves toward the exhaust end of the stroke, and previous to 95 the full stroke consummation the exhaust port is opened, as is common in two cycle engines, and the actuating charge of burned gases has reduced to about two pounds, gage pressure when the air inlet port is opened 100 by the movement of the piston. The air of the scavenging charge then is admitted at practically a constant pressure of about three pounds at the exhaust end of the cylinder, said air being admitted against 105 curved baffle projections on the piston head and diverted toward the cylinder head of the engine on that end. A volume of about fifty per cent. in excess of the cubic contents will be admitted to the combustion 110 chamber, and practically all of the burned products and one-third of the air injected will pass from the cylinder. As soon as the piston closes the air admission port and the exhaust port, there is admitted to the cylinder the measured amount of fuel from the measuring apparatus under compression which will be all entrapped, as all ports of egress are then closed, and this fuel will at once expand until the pressures are equalized, 115 and then the fuel admission port is mechanically closed and the piston in its motion completes the period of compression, and the mixture of the fuel and air is ignited in any usual manner. But I prefer a 120 multiple electric ignition with about four igniters to each cylinder of twenty four inch diameter or over, which are not shown in the drawings.

In operating the engine, and beginning at 120

the inert stage of no fuel in the cylinders, and with the piston 8 in the position shown in Fig. 1, I provide the valve 2 on each end of the cylinder 7 for the admission of a compressed expansible gas, in this instance at the upper end of the cylinder 7, which will force the piston 8 to the bottom and give the crank shaft about one half of a rotation and thus fill the other end of the cylinder with an expansible charge of air and fuel, through lower valve 1, in a manner hereinbefore described; and as this will at the proper position explode the engine will be in operation, and at the moment of the first explosion, the high pressure gas admission valves will be closed by the operator, and the engine then will operate under the cycles of explosive operation. As the high pressure valves are under control so as to admit the gas into the cylinder at a pressure at either end of the cylinder as desired to suit the exigencies of rotation, the engine will start in either direction and continue so long as the fuel is supplied and the firing device is connected.

To reverse the engine when in motion, I disconnect the firing device and allow the engine to come to a full or near full stop, and then reverse the explosive firing device. This will cause the firing or explosive impulse to be so timed as to cause an explosion at the proper time to actuate the engine in the opposite direction with certainty, as there will be no contaminating gases to cause a misfire of the charge of air and fuel. In the construction of the long piston of the engine, I provide means for cooling the piston ends with a circulation of water, and each piston pumps the circulating water for its own cylinder cooling, by means of a combination of tubes with suitable check valves in them to form suction and delivery sides automatically as the piston is propelled from end to end of the stroke, as hereinbefore described. These tubes are connected to the ends of the cross head trunnions, and in this manner the cooling water of each cylinder is independent of the other, and if one is non-operative the others will not be affected.

Having thus described my invention, what I claim as new and desire to secure by Letters Patent, is:—

1. In an internal combustion engine, means controlled by the engine shaft for supplying a measured combustible charge under pressure to the engine, means for varying the measure of said charge manually, means controlled by the engine shaft for admitting the charge to the cylinder, and means for reversing the engine by changing the time of admission of the charge.

2. In an internal combustion engine, means controlled by the engine shaft for

supplying a measured combustible charge under pressure to the engine, means for varying the measure of said charge manually, means controlled by the engine shaft for admitting the charge to the cylinder, and means for reversing the engine by changing the time of admission of the charge, said reversing means being disposed intermediate the engine shaft and the charge admission valve.

3. In an internal combustion engine, means controlled by the engine shaft for supplying a measured combustible charge under pressure to the engine, means for varying the measure of said charge manually, means controlled by the engine shaft for admitting the charge to the cylinder, and means for reversing the engine by changing the time of admission of the charge, said means comprising an admission valve, an eccentric controlling the movement of said valve and operated from the engine shaft, and mechanism for shifting the position of said eccentric relative to said engine shaft.

4. In an internal combustion engine, means controlled by the engine shaft for supplying a measured combustible charge under pressure to the engine, means for varying the measure of said charge manually, means controlled by the engine shaft for admitting the charge to the cylinder, and means for reversing the engine by changing the time of admission of the charge, said means comprising an admission valve, an eccentric controlling the movement of said valve and operated from the engine shaft, and mechanism for shifting the position of said eccentric relative to said engine shaft, said shifting mechanism comprising coacting splined elements adapted to shift the position of said eccentric at will.

5. In an internal combustion engine, means controlled by the engine shaft for supplying a measured combustible charge under pressure to the engine, means for varying the measure of said charge manually, means controlled by the engine shaft for admitting the charge to the cylinder, and means for reversing the engine by changing the time of admission of the charge, said means comprising an admission valve, an eccentric controlling the movement of said valve and operated from the engine shaft, and mechanism for shifting the position of said eccentric relative to said engine shaft, said shifting mechanism comprising a longitudinally movable sleeve splined exteriorly and interiorly with opposite pitches and engaging corresponding grooves in coacting elements, one geared to the engine shaft and the other carrying said eccentric.

6. In an internal combustion engine, a

piston, means for supplying a combustible charge to either end thereof under pressure sufficient to cause a movement of said piston due to said pressure, and manually operated means for first admitting said charge to either end of said piston at will.

7. In an internal combustion engine, a source of fuel supply under pressure, an engine cylinder, a double ended piston therein, valves at each end of said cylinder for controlling the admission of said gas

under pressure to said cylinder ends, valve rods therefor, an eccentric for operating either of said valve rods to open its valve, shiftable means connected with the engine 15 drive shaft for timing said eccentric, and means intermediate said eccentric and rods manually shiftable to disconnect said eccentric and rods.

In testimony whereof I affix my signature. 20

LYMAN S. STEVENS.
